US0D1077940S

(12) **United States Design Patent** (10) Patent No.: **US D1,077,940 S**
(45) Date of Patent: ** Jun. 3, 2025

(54) **SCALE MODEL OF CONSTRUCTION VEHICLE**

(71) Applicant: **Volvo Construction Equipment AB**, Eskilstuna (SE)

(72) Inventors: **Jonas Fredberg**, Gothenburg (SE); **Aydin Mert**, Johanneshov (SE); **Jerry Zhang**, Zaozhuang (CN); **Martin Zheng**, Jinan (CN); **Peter Reuterberg**, Marstrand (SE)

(**) Term: **15 Years**

(21) Appl. No.: **35/521,061**

(22) Filed: **May 26, 2023**

(80) **Hague Agreement Data**

Int. Filing Date: **May 26, 2023**
Int. Reg. No.: **DM/229847**
Int. Reg. Date: **May 26, 2023**
Int. Reg. Pub. Date: **May 31, 2024**

(51) **LOC (15) Cl. 21-01**

(52) **U.S. Cl.**

USPC **D21/537**; D15/23; D15/25

(58) **Field of Classification Search**
